UNITED STATES PATENT OFFICE.

PHILANDER B. ROYS, OF PULTNEYVILLE, NEW YORK.

LINE-THROWING PROJECTILE.

SPECIFICATION forming part of Letters Patent No. 310,852, dated January 13, 1885.

Application filed May 5, 1884. (No model.)

To all whom it may concern:

Be it known that I, PHILANDER B. ROYS, of Pultneyville, in the county of Wayne and State of New York, have invented a new and 5 useful Improvement in Continuous Line-Throwing Projectiles; and I do hereby declare that the following is a full, clear, and exact description of the same.

My invention is a continuous projectile for 10 life-saving service, and for like purposes. It is intended to be used as a projectile for throwing a line from ship to shore, or the reverse, or from ship to a person overboard, or from one ship to another, or a life-preserved to a 15 person overboard.

In the accompanying drawings, Figure 1 shows a central longitudinal section of the projectile. Figs. 2, 3, 4, and 5 represent the parts of which it is composed detachable from 20 each other. Fig. 6 represents the stand from which the projectile is fired. Fig. 7 shows the head of the projectile, with a series of hooks pivoted thereto, forming a grapple.

In these drawings, B represents the case or 25 body of the projectile, this being a tube of any suitable metal, as iron or steel, and of a length required for the work which it is to perform. In it is placed most of the material, the combustion of which is to form the power by which 30 the projectile is driven. A head, A, of conical or tapering form, and preferably of wood, is inserted into a threaded socket in the forward end of this tube to cover the cartridge of the projectile. Just in rear of this head is 35 an air-chamber, C, for the purpose of giving buoyancy to the projectile and to cause it to float upon the water. In the remaining part of the case is placed an inside case (marked E) of paper or wood, or any suitable material 40 adapted to hold the combustible ingredients which are to form the gases and to keep them dry under all circumstances. The butt of the case (marked G) is externally screw-threaded, as shown at F, and upon this is screwed a supplemental case having an interior thread. 45 This supplemental case is made of malleable iron or brass, and the bottom of it is funnel-shaped, as shown at H. It communicates with a hollow nipple, h, which projects axially to 50 the rear, and is provided with a cap, k, adapted

to fit over it and make a water-tight joint. The rear end of the supplemental case is screw-threaded to receive a plug, K, in which are set the ends of a prolonged wire loop, I, to which the line is attached by means of a snap-hook, 55 L. The case E, which contains the gas-producing ingredients, is preferably made with a conical end and hollow nipple adapted to fit the conical seat of the outer case, G. A cap, J, Fig. 5, is provided also, to cover the rear 60 end of the case G and preserve the ingredients from moisture, which may be made of brass or rubber. The hollow nipple or tube h forms an extended escape for the gases, and serves to increase the power as well as to direct the 65 course of the projectile, and the extended loop forms a line-traveler on which the line moves as the projectiles start.

When the projectile is fired from the shoulder, I may use any desired form of support; 70 but ordinarily the supporting-frame shown in Fig. 6 will be used. This consists of a slotted forward support, 1, hinged to a rear support, 2, these being mounted upon legs 3. An extensible brace, 4, supports the forward hinged 75 extension upon the legs and allows the proper change in the elevation of the projectile. Braces 5 may be used to steady the support when it is in position. The projectile is laid upon the support, as shown in dotted lines in 80 Fig. 6, and the charge is ignited by a fuse, or in any convenient way. For this purpose a hammer, 7, may be set upon the rear part of the supporting-frame.

The legs heretofore described may be made 85 extensible, as shown in Fig. 6. A small standard, 8, pierced with a series of holes equally distant apart, serves as a friction-primer for igniting the projectile when a cap is not used. 90

As shown in Fig. 7, I may provide a series of hooks for the shell of the head of the projectile, which may rest in slots therein, and so arranged as to be thrown outward after the projectile has been fired and landed, the sudden 95 stoppage effecting this. These hooks form a grapple and hold the projectile where it falls.

I claim—

1. In a projectile of the class described, the combination of the body B, provided with 100

suitable head, the independent case E, contained within the case B, adapted to receive the combustible material, the supplemental casing G, adapted to the end of the body B, 5 and an extended loop, I, rigidly connected to the supplemental casing G, all substantially as described.

2. In a projectile of the class described, the combination of the body B and suitable head, 10 a case, E, contained within the case B, adapted to receive the combustible material, and an air-chamber, also contained within the body B, substantially as described.

3. In a projectile of the class described, the 15 combination of the body B, provided with the

head A, the independent case E within the case B, containing the combustible material, constructed substantially as described, the supplemental casing G, adapted to the body B, and having the conical seat, and the hollow nipple 20 h, all the parts being arranged and operating substantially as described.

In testimony whereof I have signed my name to this specification in the presence of two subscribing witnesses.

PHILANDER B. ROYS.
